UNITED STATES PATENT OFFICE

163,935

INSTRUMENT PANEL FOR AUTOMATIC
MACHINE TOOLS

Ralph E. Cross, Grosse Pointe Shores, Mich.

Application April 14, 1950, Serial No. 9,219

Term of patent 14 years

(Cl. D26—5)

To all whom it may concern:

Be it known that I, Ralph E. Cross, a citizen of the United States of America, residing at Grosse Pointe Shores, in the county of Wayne and State of Michigan, have invented a new, original, and ornamental Design for Instrument Panel for Automatic Machine Tools, of which the following is a specification, reference being had to the accompanying drawing, forming a part thereof, wherein:

Figure 1 is a perspective view of the front of an instrument panel for automatic machine tools, showing my new design; and

Figure 2 is a top edgewise view of the instrument panel.

The broken-line illustration is for illustrative purposes only. The right-hand view is similar to the left-hand view shown in Fig. 1 and the bottom is similar to the top view shown in Fig. 2.

I claim:

The ornamental design for an instrument panel for automatic machine tools, substantially as shown and described.

RALPH E. CROSS.
